METHOD OF RECOVERING SELECTIVE SOLVENTS

Walter V. Stearns, White Plains, N. Y., assignor to The M. W. Kellogg Co., Jersey City, N. J., a corporation of Delaware

Application December 31, 1947, Serial No. 795,061

9 Claims. (Cl. 202—42)

1

This invention relates in general to the art of solvent fractionation of oils and more particularly to an improved process for separating the solvent from an oil fraction and from an anti-solvent such as water. The invention is particularly concerned with the treatment of petroleum oils, for example, petroleum oils boiling above the naphtha, kerosene, and gas oil ranges. The process of the present invention provides for separating the feed oil into at least two fractions, an extract phase of highly aromatic character and a raffinate phase containing oils more paraffinic than the original charge.

It is well known in the art to treat mineral oils, particularly petroleum lubricating oils, with solvents which have the ability to segregate the relatively more aromatic fractions from the relatively more paraffinic fractions. In these processes it is usual to employ solvent which have a preferential selectivity for the more aromatic type compounds, as for example, solvents of the class of phenol, cresol, aniline, nitro benzene, beta beta dichlor diethyl ether, furfural, and the like. Solvent mixtures of these substances are employed as well known mixtures containing materials of the class of liquefied normally gaseous hydrocarbons. Solvent modifying agents of the class of water, alcohols and glycols, referred to herein as anti-solvents are also used.

In these processes it is the usual procedure to introduce the oil, as for example the lubricating oil, into the bottom of a solvent treating tower, since it is usually lighter than the solvent, and to introduce the solvent into the top of the tower. The oil being the lighter phase flows upwardly through the tower, intimately contacting the downflowing solvent. A raffinate phase completely saturated with solvent is removed from the upper part of the tower and a solvent extract phase is removed from the lower part of the tower. It is, of course, desirable to secure a raffinate and extract phase having as high a concentration as possible of the paraffinic materials and aromatic materials respectively. It is, therefore, necessary to employ a solvent of suitable selectivity. The most commonly used solvent, phenol, does not have satisfactory selective characteristics unless its solvent power is reduced by the addition of a suitable diluent, or anti-solvent such as water. The present invention is concerned with an improved process for separating the extract phase withdrawn from a solvent extraction step like that described above into its components of extract, solvent, and anti-solvent. The process of my invention is a dis-

5 tinct improvement over the known processes in the art in that it is possible to accomplish the fractionation process with about 35 per cent less furnace capacity than has heretofore been required for separating solvent from the extract phase.

10 The invention is not limited to any one particular combination of solvent and anti-solvent but relates to any extraction system in which a solvent and an anti-solvent having a boiling point lower than that of the extract must be separated therefrom by evaporation. The system of employing furfural and water is an example. Furthermore, the process is applicable where the water, or other material present in addition to the extract and solvent, is an impurity to be separated rather than an anti-solvent serving a useful purpose.

15 The process of my invention may be readily understood by reference to the attached drawing showing apparatus suitable for its practice. For the purpose of illustrating this invention it is assumed that the feed oil is a petroleum oil (preferably, but not necessarily boiling above the 20 naphtha and gas oil range), and the solvent is phenol which is typical of the class having a preferential selectivity for the more aromatic type compounds and having suitable characteristics so that the solvent may be readily separated from the oil. The phenol extract phase comprised mostly of phenol but having substantial percentages of extract oil and water, enters the system through line 10 and is heated in two successive steps in heat exchangers 11 and 12 25 which causes the liquid extract to be partially vaporized. The liquid-vapor mixture is introduced into flash drum 13 for purposes of separating phenol and water vapors from that part of the extract phase which remains in liquid condition. The vapors are withdrawn from flash drum 13 through overhead line 14 and introduced into a fractionation tower 15 which is provided with a number of bubble trays indicated by horizontal dashed lines 16. Unvaporized liquids are withdrawn from flash drum 13 through line 17, passed 30 through heat exchanger 18, and are introduced into fractionation tower 15 at a point several trays lower than that at which vapor line 14 enters tower 15. The flow of liquid through line 17 is controlled by a liquid level control valve 19, which opens and closes in response to variations in the position of liquid level float 20 within tower 15. Shut-off valve 21 is provided for 35 emergency use. Fractionation tower 15 effectively separates the

phenol extract phase into a liquid fraction of pure phenol and oil, and a vapor phase which is an azeotropic mixture of water and phenol. The phenol and oil phase is withdrawn from the bottom of tower 15 through line 22 and pumped by pump 23 to an upper section 24 of tower 15. Upper section 24 is entirely separated from balance of tower 15 by separating partition 25 and is used for the separation of phenol and oil.

The phenol-water vapor is withdrawn from the upper end of the lower section of tower 15 through line 27, cooled and condensed by heat exchanger 28, and stored in phenolic water storage drum 29. Control valve 29a regulates the withdrawal of phenolic water vapor through line 27 and is automatically controlled in response to pressure conditions within lower section of tower 15 by a conventional pressure responsive means 29b so as to maintain a desired pressure within tower 15. Some phenolic water is returned by line 30 and pump 31 to tower 15 to serve as a reflux liquid, the amount of reflux being controlled by a control valve 32 and a flow controller 33 preferably operated by temperature control means 34.

In order to conveniently maintain a proper amount of phenolic water in phenolic water storage drum 29 a supply line 35 is connected to reflux line 33 for either withdrawing or adding phenolic water. In case the amount of phenolic water becomes excessive, it may be withdrawn through line 36 which connects storage line 35 with reflux line 33 on the high pressure side of pump 31. A valve 37 in line 36 is automatically operated through conventional operating means 38 by liquid level control float 39 within phenolic water storage drum 29 so as to maintain a substantially constant level therein. If it is desired to introduce additional phenolic water for phenol recovery, it may be introduced into the system by opening valve 40.

It will be understood, of course, that flash drum 13 could be eliminated and that the incoming phenol extract could be introduced as a mixture of liquid and vapor coming directly from line 10 into tower 15. However, employment of flash drum 13 for separating the liquid and vapor and introducing them into the tower 15 at different levels increases the efficiency of the fractionation and makes possible the use of heat in heat exchanger 12 where it is most urgently needed.

A liquid level recorder 26 may be usefully employed to indicate the liquid level in the bottom of tower 15.

The flow of the water-free mixture of phenol and oil through line 22 to upper section 24 is controlled automatically by flow control valve 41 and, if necessary, is mixed with additional phenol introduced through line 42. Inside upper section 24 phenol oil mixture passes downwardly through a series of bubble trays 43 under substantially higher pressure and temperature conditions than existed in the water fractionating section 15. A substantial amount of liquid is retained in a trapout section 44, the liquid level being recorded by liquid level recorder 45. Liquid is continuously withdrawn from trapout section 44 through line 46 and circulated by pump 47 through a furnace 48 and back to the bottom of upper section 24 via line 49. Dual flow controllers 50 and 51 are provided to control the rate of circulation through furnace 48. The bulk of the phenol is vaporized in the furnace 48 and the vapor is collected in the upper flash section

24 of the tower 15. The vapors separated here flow upwardly through the vapor passages 52 and the trays 43 in which the vapor is desuperheated and some phenol is vaporized from the descending feed stream.

The phenol vapor from above the trays 43 leaves the tower by means of line 53 and is passed to reboiler 54 in which it is totally condensed. The heat given off in this condensation vaporizes phenol from the downflowing stream flowing from the tower by means of line 55; the stream flowing in line 55 is then returned to the tower for separation. Some of this vapor is employed in the tower for vaporizing the phenol-water azeotrope. The excess vapor is withdrawn through line 65. Liquid phenol is withdrawn via line 60, through valve 61 at a rate controlled by liquid-level controller 62. Likewise, the withdrawal of vapors from upper flash section 24 through line 53 is controlled by means of valve 63 which is controlled automatically in response to the pressure-control means 64.

Since the vapor entering line 65 comes from a point within fractionation tower 15 under the last bubble tray 16a, it is substantially pure phenol because all the water has been removed by vaporization at a higher point within the tower 15 and all the oil is liquid under temperature and pressure conditions within tower 15. The heat contained in the phenol vapor is usefully employed in heat exchanger 12 as a means for heating the incoming extract phase, at a rate which may be governed by valve 67; valve 67 may be controlled by temperature-responsive means 68 to divert phenol vapor through line 66 if temperatures seem to justify it. The rate of vapor withdrawal from line 65 may be controlled by line 69 which is itself controlled according to the pressure within tower 15 by means of pressure-responsive means 70. If the phenol vapor were not removed at this point it would rise through tower 15 until liquefied in the upper portion thereof. In so doing it would transmit heat to the various bubble trays higher up in the tower but the heat thus transferred would not serve a particularly useful purpose since tower 15 generally has an excess of heat, but would rather require more reflux and more cooling water. The same heat is much more usefully employed in partially vaporizing the extract phase coming in through line 10. Moreover, all phenol, an excess of that required for the constant boiling of phenolic-water mixture from tower 15 withdrawn through line 27 would eventually have to find its way from tower 15 through line 22 to upper section 24 as in a phenol-oil mixture. It would then be necessary for the capacity of upper section 24 and furnace 48 to be sufficiently great to distill off all of the phenol not removed in the phenolic-water mixture. In accordance with the present invention, however, a substantial portion of the phenol is separated from the oil in the lower portion of tower 15 rather than in upper section 24 so that the duty imposed on upper section 24 and furnace 48 is much smaller as a result. It is possible, therefore, to effect substantial savings in initial investment and operation of upper section 24 and furnace 48.

An example of these savings shown in the design of a large refinery unit for phenol treating East Texas deasphalted oil resulted in great economies which can be illustrated by the following figures:

In a phenol treating plant having a capacity of 6,160 barrels per stream day the extract phase

consisted of Ph. L. 222,530 lbs. per hr., water 11,450 lbs. per hr., extract oil 24,000 lbs. per hr., total 257,980 lbs. per hr. This extract phase left the phenol counter-current extraction tower at a temperature of 220° F. and, at this temperature, entered heat exchanger 12. Heat exchanger 12 operates under a duty of 16,704,000 B. t. u. per hr. and increases the temperature of the extract phase mixture to 310° F. to produce the following mixture, Ph. V. 1890 lbs. per hr., steam 3510 lbs. per hr., Ph. L. 227,332 lbs. per hr., water 8,251 lbs. per hr., extract oil, 24,000 lbs. per hr., total 264,983 lbs. per hr. At a temperature of 310° F. and a pressure of 5 lbs. gauge the extract phase is separated into vapors passing through line 14 which consist of Ph. V. 1890 lbs. per hr., steam 3510 lbs. per hr., total 5400 lbs. per hr., and liquids entering the tower through line 17 which consist of Ph. L. 227,332 lbs. per hr., water 8,251 lbs. per hr., extract oil 24,000 lbs. per hr., total 259,583 lbs. per hr. Tower 15 is maintained at a pressure of 5 lbs. gauge and has a temperature gradient ranging from 230° F. at the upper end near point at which the azeotropic vapors leave through line 27 to a temperature of 380° F. in the bottom portion of tower 15 near the point at which liquid phenol and oil is withdrawn through line 22. The lower end of dryer tower 15 is maintained at 380° F. by circulating 305,000 lbs. per hour of liquid through heat exchanger 54 in which 30,500,000 B. t. u. per hour are transferred from phenol vapor in line 53 to phenol oil liquid in line 55 with the result that the phenol vapor is condensed and the phenol-oil liquid loses about half its phenol in the form of phenol vapor part of which passes upwardly through bubble trays 16 and part is withdrawn through line 65 in order to achieve the efficiencies which the present invention has for its object.

85,270 lbs. per hour of phenol vapor at a temperature of 380° F. is withdrawn through line 65 and condensed in heat exchanger 12 to phenol liquid at 380° F., thus providing 16,604,000 pounds per hour for the partial vaporization of incoming extract phase.

Within dryer tower 15 the extract phase is separated into azeotropic vapor withdrawn through line 27 which consists of Ph. V. 1886 lbs. per hr., steam 14,113 lbs. per hr., total 15,999 lbs. per hour. This constant boiling mixture is about 89% steam and 11% phenol vapor at a pressure 5 lbs. gauge. All of the water is removed from the extract phase in this manner.

Dry extract solution will be withdrawn from the bottom of the tower through line 22 at the rate of Ph. L. 142,380 lbs. per hr., extract oil 24,000 lbs. per hr., total 166,380 lbs. per hour.

Upper section 24 operates under a pressure of 25 lbs. per square inch with a temperature of about 435° F. at the upper end and 560° F. at the lower end. Phenol vapor is withdrawn at the rate of 40,500 lbs. per hour through line 53 and condensed in dryer tower reboiler 54. The extract oil product withdrawn from the bottom of upper section 24 contains some phenol the proportion being about as follows: Ph. L. 1880 lbs. per hr., extract oil 24,000 lbs. per hr., total 25,880 lbs. per hour. The remainder of the phenol may be separated from the extract oil by any conventional means for instance, by steam stripping.

It will be seen that almost 1/3 of the phenol is separated from the extract in the lower part of dryer tower 15. The consequent lowering of duty on upper section 24 and furnace 48 results in a saving in the cost of the furnace which usual-

ly runs about 4 or 5 times the total cost of the heat exchanger 12 and reboiler 54.

Moreover, the cooler which was formerly required to cool the phenol after recovery is no longer needed. In previous installations all of the phenol passed through furnace 48 with the result that a great deal of heat was introduced into the system; under the present invention a large proportion of the phenol is withdrawn through line 65 and the duty on furnace 48 is greatly reduced so that less heat is introduced into the system and the necessity for cooling phenol is eliminated.

The annual savings because of reduced consumption of the fuel gas from the furnace and the addition of water to the phenol cooler results in the reduction of operating costs which far exceeds the initial savings in capital investment. While the process of the following invention is particularly applicable to the treatment of heavy petroleum oil fraction to separate the more aromatic components from the more paraffinic, it is to be understood that the process may be usefully employed in other solvent fractionation processes in which it is necessary to recover an extract from an extract phase containing an extract, a lower-boiling solvent, and an anti-solvent.

I claim:

1. In the fractionation of a solvent extract solution containing extract, a lower-boiling solvent and an anti-solvent which has a boiling point lower than said solvent, wherein said solution is subjected to fractional distillation in a vertically extended fractionation zone to separate a top distillate fraction containing substantially all of said anti-solvent, and wherein a residue of solvent and extract is withdrawn from the lower end of said fractionation zone, the improvement which includes the steps of: withdrawing a liquid sidestream from said fractionation zone at a point sufficiently below the point of introduction of said solvent extract solution to obtain a liquid substantially free of said anti-solvent; heating said liquid sidestream to vaporize a substantial part of the solvent content thereof; returning at least part of said solvent vapor to said fractionation zone at a point not higher than the point of withdrawal of said liquid sidestream, and withdrawing a vapor sidestream of substantially pure solvent from said fractionation zone at a point sufficiently below the point of introduction of said extract solution and sufficiently near the point of introduction of said solvent vapor to be substantially free of said anti-solvent.

2. A method as described in claim 1 in which said solvent is a phenol and said anti-solvent is water.

3. A method as described in claim 1 in which said solvent is furfural and said anti-solvent is water.

4. A method as described in claim 1 in which said bottoms liquid is heated sufficiently to vaporize a maximum of substantially pure solvent vapor; a portion of said solvent vapor is permitted to rise through said first fractional distillation tower to provide distillation heat therein; and the excess of said solvent vapor is withdrawn in said vapor sidestream.

5. The combination as described in claim 1 in which said solvent vapor stream from said fractional distillation zone is at least partially condensed by indirect heat exchange with said solvent extract solution prior to the introduction of said extract phase into said first fractional distillation zone.

6. In the fractionation of a solvent extract solution containing extract, a lower-boiling solvent, and an anti-solvent which has a boiling point lower than said solvent, wherein said solution is subjected to a first fractional distillation in a vertically extended fractionation zone to separate a top distillate fraction containing substantially all of said anti-solvent, and wherein the residue of said first fractionation is withdrawn from the lower end of said fractionation zone and subjected to a second fractional distillation to separate substantially pure solvent vapor, the improvement which includes the steps of: withdrawing a liquid sidestream from said fractionation zone at a point sufficiently below the point of introduction of said solvent extract solution to obtain a liquid substantially free of said anti-solvent; passing said liquid sidestream through a reboiler in indirect heat exchange with said solvent vapor from said second fractional distillation to vaporize a substantial part of the solvent content of said liquid sidestream; returning at least part of said solvent vapor to said fractionation zone at a point not higher than the point of withdrawal of said liquid sidestream; and withdrawing a vapor sidestream of substantially pure solvent from said fractionation zone at a point sufficiently below the point of introduction of said extract solution and sufficiently near the point of introduction of said solvent vapor to be substantially free of said anti-solvent.

7. In the fractionation of a solvent extract solution containing extract, a lower-boiling solvent, and an anti-solvent which has a boiling point lower than said solvent, wherein said solution is subjected to a first fractional distillation in a vertically extended fractionation zone to separate a top distillate fraction containing substantially all of said anti-solvent, and wherein the residue of said first fractionation is withdrawn from the lower end of said fractionation zone and subjected to a second fractional distillation to separate substantially pure solvent vapor, the improvement which includes the steps of: withdrawing a liquid sidestream from said fractionation zone at a point sufficiently below the point of introduction of said solvent extract solution to obtain a liquid substantially free of said anti-solvent; passing said liquid sidestream through a reboiler in indirect heat exchange with said solvent vapor from said second fractional distillation to vaporize a substantial part of the solvent content of said liquid sidestream; returning at least part of said solvent vapor to said fractionation zone at a point not higher than the point of withdrawal of said liquid sidestream; and withdrawing a vapor sidestream of substantially pure solvent from said fractionation zone below the point of withdrawal of said liquid sidestream.

8. In the fractionation of a solvent extract solution containing extract, a lower-boiling solvent, and an anti-solvent which has a boiling point lower than said solvent, wherein said solution is subjected to a first fractional distillation in a vertically extended fractionation zone to separate a top distillate fraction containing substantially all of said anti-solvent, and wherein the residue of said first fractionation is withdrawn from the lower end of said fractionation zone and subjected to a second fractional distillation to separate substantially pure solvent vapor, the improvement which includes the steps of: withdrawing a liquid sidestream from said fractionation zone at a point sufficiently below the point of introduction of said solvent extract solution to obtain a liquid substantially free of said anti-solvent; passing said liquid sidestream through a reboiler in indirect heat exchange with said solvent vapor from said second fractional distillation to vaporize a substantial part of the solvent content of said liquid sidestream; returning at least part of said solvent vapor to said fractionation zone at a point not higher than the point of withdrawal of said liquid sidestream; withdrawing a vapor sidestream of substantially pure solvent from said fractionation zone at a point sufficiently below the point of introduction of said extract solution and sufficiently near the point of introduction of said solvent vapor to be substantially free of said anti-solvent; and passing at least part of said solvent vapor through a reboiler in indirect heat exchange with incoming solvent extract solution to condense said vapor and heat said solution prior to the introduction of the latter into said fractionation zone.

9. A method as described in claim 6 in which temperatures lower than the boiling point of said solvent are maintained in the region of said fractional distillation zone from which said top distillate fraction is withdrawn; and temperatures at or above the boiling point of said solvent are maintained in the region in which said solvent vapor is introduced into said fractionation zone.
